UNITED STATES PATENT OFFICE.

PATRICK KENEHAN, OF MONTREAL, CANADA.

DUMPING-WAGON.

SPECIFICATION forming part of Letters Patent No. 779,085, dated January 3, 1905.

Application filed August 25, 1904. Serial No. 222,058.

To all whom it may concern:

Be it known that I, PATRICK KENEHAN, a subject of the King of Great Britain, residing in the city and district of Montreal, in the 5 Province of Quebec, Canada, have invented certain new and useful Improvements in Dumping-Wagons; and I do hereby declare that the following is a full, clear, and exact description of the invention, such as will enable others skilled in the art to which it 10 pertains to make and use the same.

This invention relates to new and useful improvements in metallic dumping-wagons; and it consists in certain features of novelty 15 in the detail construction and arrangement thereof whereby a dumping-wagon is produced wherein the greater portion of the framing therefor and the wagon-body supported by such framing is produced from commercial steel, which may be readily obtained 20 in the open market.

The object of the invention is to produce a spring-supported dumping-wagon of metal which will be supported by a bolster placed 25 intermediate the supporting-axles, the body portion being rockable upon such supporting-bolster independently of the bed-frame used for supporting the body.

Referring to the annexed drawings, in 30 which similar numerals of reference indicate corresponding parts, Figure 1 is a side elevational view of a dumping-wagon of the character described without its supporting-wheels. Fig. 2 is a transverse sectional view of Fig. 35 1 on line 2 2. Fig. 3 is a similar view on line 3 3 looking in the direction indicated by the arrow. Fig. 4 is a detached detail of the combined body brace and clip used for connecting the tilting body upon the supporting-bolster. 40 Fig. 5 is a fragmentary detail illustrating the manner of connecting the rear supporting-springs with the bed-frame. Fig. 6 is a section on line 6 6 of Fig. 5. Fig. 7 is an enlarged broken detail view showing the manner 45 of supporting the rear springs upon the crank-axle. Fig. 8 is an enlarged detail view of the lifting-screw in mesh with a rockable stud adapted to be connected with the body portion of the wagon. Fig. 9 is a detail view 50 illustrating the manner of connecting the

lower end of the screw-rod shown in Fig. 8. Fig. 10 is a fragmentary detail illustrating in plan a portion of a side sill and an end sill connected therewith, showing in section a portion of the wagon-body resting upon the 55 end sill.

Referring to the parts, 1 is the front axle, provided with the springs 2, which are connected to such axle by the clips 3 and support the platform 4, upon which is mounted 60 the two elements 5 of the "fifth-wheel," so called. Above the fifth-wheel is a bolster 6, above which extends transverse truck-bolsters 7 for supporting the bed-frame. This bed-frame comprises an approximately U- 65 shaped structure consisting of the side sills 8, having the horizontal outwardly-extending flanges 9, and end sill 10, composed of a commercially-rolled angle like the side sill, but with the horizontal flange 11 projected 70 inwardly and rearwardly, so as to serve as a convenient supporting means for the front-end portion of the wagon-body 12, which wagon-body comprises the bottom plate 13, the side plates 14, and end plate 15, while a 75 releasable door 16 is provided at the rear end of such body, so that when the wagon-body is tilted to the position shown in dotted lines in Fig. 1 such end plate may be opened for the purpose of discharging the contents of 80 the wagon-body. As will be noted in Fig. 10, the end sill has its vertical and horizontal flanges split near the ends of such end sill, and the portion 10^a of such end sill is left longer than the portion 11^a thereof, so that 85 the said flange 10^a may overlap the vertical flange of the side sill and be connected therewith by suitable rivets 17, as shown, whereby the end sill is supported in position by the side sill. The rear spring 18 is connected with 90 the side sills by means of brackets 19, within which the front ends of such rear springs 18 are pivotally supported upon the pintles 20, as shown in Fig. 1. The rear ends of the springs 18 are connected with the slidable 95 plate 21, which is connected, by means of the clips 22, with the horizontal flange 9 of the side sill, so that such plate 21 is slidably mounted upon the said sill to permit more or less vibratory movement of the rear springs. 100

The intermediate portion of the rear springs are connected, as shown in Fig. 7, by means of the clips 23, with the upper horizontally-projecting crank portion 24 of the rear axle 5 25. Extending forwardly of the brackets 19 are straps 26, which form clip 27, which serve as bearings for the circular portion 28 of the transversely-extending bolster 29, which bolster is connected by such clips 27 to 10 and is thereby supported from the side sills before referred to.

For the purpose of locking the body 12 upon its supporting-bolster 29 clips 30, which form side braces for the body, extend downwardly, 15 as shown in Figs. 2 and 4, and are connected by means of the plate 31 and screw-threaded portions 32 upon said transversely-extending bolster 29, a rivet-opening 33 being provided in such member 30, through which the rivet 20 34, connecting the side and bottom plates of the wagon-body, is projected. Connected with the upper portion of the member 30 and extending approximately to the outer end of the bolster 29 is a brace 35, while an intermediate brace 36 serves as a strengthening means therefor for uniting the body of such supporting-bolster. Intermediate the end sill and such supporting-bolster there are connected with the side walls 14 of the body clips 25 37, in which are rockably mounted the studs 38, which studs are provided with the trunnions 39 and are internally screw-threaded, as shown in Fig. 8. If desired, the upper portion 40 of the studs 38 may be externally 30 screw-threaded and a sleeve 41 secured thereupon, as shown in the fragmentary detail, Fig. 8. Connected with the side sills are brackets 42, within which are mounted the transversely-extending shaft 43, carrying bevel-gears 44 near opposite ends thereof, with which bevel-gears mesh other gears, 45, which are locked upon the lower end of the screw-threaded rod 46, a non-circular portion 47 being provided upon the shaft 43, upon which 40 may be mounted the crank 48 for rotating said shaft. To support the lower end of the rod 46, the bracket 49 is rockably mounted upon the shaft 43 and has bearings 50 and 51 therein provided, respectively, for the shaft 45 50 43 and the lower end of the rod 46, while said bevel-gear 45 is mounted within the approximately elliptical opening 52 in said bracket 49. As the bracket 49 is rockably mounted upon the shaft 43 and the screw-threaded stud 55 38 is also rockably mounted within its supporting-clips 37, it is evident that when the body is being tilted the pinion 45 will ride circumferentially of the pinion 44, so that the rod 46 may occupy the position shown in dotted lines in Fig. 1, thus avoiding destruction of said rod during the tilting of the wagon-body, at which time the rear-end portion of the wagon-body will descend within the crank portion of the rear axle, which is bent down-

wardly for the purpose of permitting such 65 descent.

The operation of my improved wagon is as follows: The body being supported as shown in full lines in Fig. 1 and filled when it is desired to dump the contents thereof, all that 70 is necessary is to apply the crank 48 to rotate the shaft 43, whereupon, through the gears 44 and 45, a screw-threaded rod 46 will be rotated in engagement with the stud 38, which is fixed to the wagon-body, thereby raising 75 the front end of the wagon-body from its position of rest upon the flange 11 and bolster 29 to the position shown in dotted lines in Fig. 1, in which position the weight is carried by the bolster 29, which, as will be noted, 80 is substantially midway between the front and rear end of the side sills, and such bolster will rock in its bearings supported from the side sills during the tilting of the wagon-body.

While I have shown in the accompanying 85 drawings the preferred form of my invention, it will be understood that I do not limit myself to the precise form shown, for many of the details may be changed in form or position without affecting the operativeness or 90 utility of my invention, and I therefore reserve the right to make all such modifications as are included within the scope of the following claims or of mechanical equivalents to the structures set forth. 95

Having described my invention, what I claim, and desire to secure by Letters Patent, is—

1. In a dumping-wagon, a metallic bed-frame formed of angles, a plurality of bearings thereon, a rockable bolster supported in said bearings, a body supported on said bolster, clips on the sides of said body, rockable screw-threaded bearing-blocks supported by said clips, rockable screw-threaded lifting-rods, and means for rotating said lifting-rods. 100

2. In a dumping-wagon, a metallic substantially U-shaped bed-frame formed of angles, a plurality of bearings thereon, a rockable bolster supported in said bearings, a body supported on said bolster, clips on the sides of said body, rockable screw-threaded bearing-blocks supported by said clips, rockable screw-threaded lifting-rods, and means for rotating said lifting-rods. 110

3. In a dumping-wagon, a metallic bed-frame of substantially U shape, comprising side sills and an end sill, bearings intermediate the ends of said side sills, a rockable bolster mounted therein, a body rigidly mounted on said bolster, sleeves mounted on said body, screw-threaded plugs connected with said sleeves, rockable screw-threaded rods engaging said plugs, gears on said rods, an operating-shaft, and gears on said shaft. 115

4. In a dumping-wagon, an angle end sill and side sills, a bolster supported by said side sills approximately midway the length there-

of, a vehicle-body mounted on said bolster, springs supporting said side sills, and means for elevating the forward end of said body.

5. In a dumping-wagon, an angle end sill and side sills, a rockable bolster supported by said side sills approximately midway the length thereof, a vehicle-body mounted on said bolster, springs supporting said side sills, and means for elevating the forward end of said body.

6. In a dumping-wagon, an angle end sill and side sills, a rockable bolster carried by said side sills, a vehicle-body rigidly connected with said bolster, supporting-springs below said side sills, rockable brackets supported by said side sills, screw-threaded rods carried thereby, screw-threaded means on said body in engagement with said rods, and means for rotating said rods.

20 7. In a dumping-wagon, angle side sills with their horizontal flanges outwardly disposed, an end sill with its horizontal flange inwardly disposed, a rockable bolster supported intermediate the ends of said side sills, a wagon-
25 body supported on said bolster and on said end

sill, a rotatable shaft between said end sill and said bolster, and means operable thereby for tilting said body.

8. In a dumping-wagon, angle side sills, an angle end sill having an integral extension bent rearwardly and secured to said side sills, a transverse rockable bolster mounted on said side sills, a vehicle-body mounted on said bolster, and a screw-threaded lifting means for said body.

30 9. In a dumping-wagon, angle side sills, an angle end sill having an integral extension bent rearwardly and secured to said side sills, a transverse rockable bolster mounted on said side sills, a vehicle-body mounted on said bolster, and a screw-threaded lifting means for said body located intermediate the end sill and said bolster.

40 In witness whereof I have hereunto set my hand in the presence of two witnesses.
